UNITED STATES PATENT OFFICE.

CATHERINE A. TRENTNOLM, OF WOBURN, MASSACHUSETTS.

COMBINED CORSET AND BRASSIERE.

1,353,660.

Specification of Letters Patent.

Patented Nov. 9, 1920.

Application filed March 20, 1920. Serial No. 367,377.

To all whom it may concern:

Be it known that I, CATHERINE A. TRENTNOLM, a citizen of the United States, residing at Woburn, county of Middlesex, State 5 of Massachusetts, have invented an Improvement in Combined Corsets and Brassières, of which the following description, in connection with the accompanying drawing, is a specification, like characters on the drawing representing like parts.

This invention relates to garments of the corset type and especially to garments of this type which are designed to meet the requirements of stout or fleshy women.

15 In some respects the garment herein illustrated is an improvement on the corset described and shown in my Patent No. 800,957, dated October 3, 1905.

My present invention has for its object 20 to provide a corset which is constructed to accommodate the flesh in the region of the breasts and at the same time to give to the wearer a form of pleasing lines.

My improved garment comprises a stayed 25 body portion which encircles the waist of the wearer and a yoke portion fitting the shoulders of the wearer, said body portion and yoke portion being united at substantially the breast line.

30 The garment is provided in the front at each side with a slit in the region of the breasts which crosses the connecting line between the body portion and the yoke portion and which extends down into the upper end 35 of the body portion and upwardly into the lower part of the yoke portion, and it has a pocket-like gusset sewed to the edges of each slit, each gusset having a tab which is adapted to overlie and be detachably secured 40 to the tab of the other gusset. The slits and pocket-like gussets permit the garment to expand at the breast line and thereby to accommodate the flesh in the region of the breasts, and by reason of the tabs and their 45 means for adjustably connecting them together, it is possible to so adjust the garment as to maintain the flesh in the region of the breasts in proper position and prevent it from crowding up over the edge of the garment.

In order to give an understanding of my invention, I have illustrated in the drawing a selected embodiment thereof which will now be described, after which the novel

features will be pointed out in the appended 55 claims.

Figure 1 is a front view showing my improved garment in use;

Fig. 2 is a view showing the garment 60 opened at the back and spread out;

Fig. 3 is a perspective view of one of the gussets and its tabs;

Fig. 4 shows the piece from which each gusset may be made;

Fig. 5 is a section on the line 5—5, Fig. 2. 65

As stated above my garment comprises a body portion which encircles the waist of the wearer and is provided with steels, bones, or other stays, and a yoke portion which fits the shoulders of the wearer.

70 The body portion of my improved garment is indicated at 1 and the yoke portion at 2. This body portion and yoke portion are connected along a division line 3 which is substantially at the breast line of the 75 wearer. The body portion 1 may be made in any suitable way and provided with the usual bones, steels or other stays indicated at 5. It is shown as constructed to be laced up at the back, as usual in corsets, and is 80 open at the front, the edges of the opening being detachably connected by the usual fastenings 6.

The yoke portion 2 is made without stays 85 and may be made of any suitable material, it being provided with openings 7 for the arms.

90 The garment is provided on each side and in a position approximately opposite each breast with a vertical slit 8, each slit crossing the division line 3 and extending downwardly into the body portion to substantially the point 80 and upwardly into the yoke portion to the point 9. Each slit is closed by a pocket-like gusset member 10 which provides for proper expansion 95 and also furnishes the desired room to accommodate the flesh in the region of the breasts. Each gusset 10 has its edges 11 sewed to the edges of the slit 8. As stated 100 above, each gusset is in the nature of a pocket and is closed at its top edge 12 and at its lower edge 13. Each gusset also has a tab 14 secured to its outer end, and the two tabs are of sufficient length so that 105 they overlap each other, as shown in the drawings. The tabs are provided with suitable detachable fastening means, such as

2
snap fasteners 15, by which they may be adjustably connected together at both their top and bottom edges. These tabs are secured to the upper portions of the gussets 10 and are preferably situated above the division line 3. When the corset is put on it will expand more or less at the slits 8 to accommodate the breasts, and after it has been laced, the wearer will place the tabs 14 in overlapping relation and adjustably secure them together in such a manner as to give the garment the desired fullness above the breast line.

It will be noted that the tabs are situated above the division line 3, and when connected they have a tendency to prevent the flesh in the region of the breasts from crowding upwardly to the top of the yoke portion, and thus assist in giving the wearer the desired line without producing any discomfort.

The gussets 10 may conveniently be made from L-shaped pieces having the shape shown in Fig. 4 by folding the pieces along the dotted line 16, and then sewing the two edges 17 together, and also the two edges 18 together. The other edges indicated at 11 are the edges which are sewed to the edges of the slit.

30 While I have illustrated herein a selected embodiment of my invention, I do not wish to be limited to the constructional details shown, as various changes in the manner

of applying the invention to a garment may be made without sacrificing any of the advantages thereof. 35

I claim:

1. A combined corset and brassière comprising a yoke portion and a stayed body portion connected together at substantially the breast line, said garment having at each side a vertical slit extending across the division line and downwardly into the upper part of the body portion and upwardly into the lower part of the yoke portion, a pocket-like gusset piece sewed to the edges of each slit, tabs extending from the ends of the gussets, and means for detachably fastening said tabs together. 45

2. A combined corset and brassière comprising a yoke portion and a stayed body portion connected together at substantially the breast line, said garment having at each side a vertical slit extending across the division line and downwardly into the upper part of the body portion and upwardly into the lower part of the yoke portion, a pocket-like gusset piece sewed to the edges of each slit, tabs extending from the ends of the gussets and situated above the breast line, and means for detachably fastening the tabs together. 55 60

In testimony whereof, I have signed my name to this specification.

CATHERINE A. TRENHOLM.
